E. B. JACOBSON.

IGNITION TIMER.

APPLICATION FILED AUG. 17, 1920.

Patented May 31, 1921.

Inventor:
Edward B. Jacobson
by Emery, Booth, James, Barney
Hillys.

UNITED STATES PATENT OFFICE.

EDWARD B. JACOBSON, OF PITTSFIELD, MASSACHUSETTS, ASSIGNOR TO J. & B. MANUFACTURING COMPANY, OF PITTSFIELD, MASSACHUSETTS, A CORPORATION OF MASSACHUSETTS.

IGNITION-TIMER.

1,379,629.

Specification of Letters Patent.

Patented May 31, 1921.

Original application filed November 8, 1918, Serial No. 261,607. Divided and this application filed August 17, 1920. Serial No. 404,179.

To all whom it may concern:

Be it known that I, EDWARD B. JACOBSON, a citizen of the United States, residing at Pittsfield, in the county of Berkshire and Commonwealth of Massachusetts, have invented an Improvement in Ignition-Timers, of which the following description, in connection with the accompanying drawings, is a specification, like characters on the drawings representing like parts.

The present invention relates to the rotor portion of apparatus of the character referred to and more particularly concerns the mounting for the brush or contact-roll. Improvement in the durability, accuracy of operation, and general efficiency of the timer constitute the objects of the invention. This application forms a division of my pending application relating to improvements in ignition timers, filed November 8, 1918, Serial No. 261,607, and relates to certain subject-matter therein disclosed and specifically reserved as the basis for a separate application for Letters Patent.

With the foregoing and other objects in view, the present invention consists in the construction, combination, arrangement, and operation of parts, as hereinafter more particularly described and shown, and pointed out in the claims.

Referring to the accompanying drawings: Figure 1 is a sectional face view of an ignition timer embodying my invention and operatively mounted upon an engine cam-shaft, the front portion of the casing being cut away;

Fig. 2, a side elevation of the rotor carrier;

Fig. 3, a front elevation of the same;

Fig. 4, a longitudinal vertical section showing the method of mounting the rotor carrier on the shaft, the front and rear portions of the rotor assembly being cut away;

Fig. 5, a sectional bottom view of the contact-arm on a longitudinal curved line;

Fig. 6, a longitudinal vertical section of the rotor portion operatively mounted;

Fig. 7, a vertical cross-section of the rotor assembly on a plane coincident with the inner face of the outer radial carrier-arm;

Fig. 8, a side elevation of the rotor assembly;

Fig. 9, a side elevation of one of the plates of the contact arm;

Fig. 10, a side elevation of the pin on which the contact-roll is mounted;

Fig. 11, an end view of the same;

Fig. 12, a view similar to Fig. 10, of a modification;

Fig. 13, an end view of the same.

The mechanism herein illustrated is designed for use in connection with a four-cylinder explosive engine having a gear-driven cam-shaft operated by the main engine shaft, but it should be understood, however, that my invention is applicable for use with motors having any number of explosion cylinders, and may be otherwise mounted and driven.

Within the casing 1 is an insulation ring 2, of which the inner rim 3 forms a suitable path over which the rotor portion travels. Arranged at regular intervals on said rim and embedded in its surface are a series of contacts 4, 4, etc., having arcuate faces forming a part of the traveled course of the rim, said contacts being suitably connected to separate binding-posts 5, 5, etc., mounted on the exterior of the casing for the attachment of appropriate electrical conductors in the usual manner.

Mounted to rotate with the cam-shaft 6 within the casing 1 is a metal carrier 7 in the form of a sleeve which is normally secured against axial movement on the cam-shaft by a transversely arranged removable pin 8 projecting through the shaft and extending at opposite ends into slots 9, 9, (Fig. 3) provided in the outer rim of the carrier. The pin 8 is secured against endwise displacement by a cup-washer 10 fitted over the outer end of the carrier and extending over the exposed ends of the pin 8, the outer end of the cam-shaft 6 which extends through the center of the cup-washer 10 being reduced and threaded to receive a pair of nuts 11, 12, which are employed to coöperate with a flat washer 13 to secure the cup-washer in position.

The carrier 7 is provided with a pair of lateral arms 14, 14, arranged thereon in spaced parallel relation and pivotally supporting at their outer ends a contact-arm, comprising preferably a pair of oppositely

arranged plates 15, 15, secured at their inner ends to the carrier-arms 14, 14, by a transversely arranged hinge-pin 16. The hinge-pin 16 has reduced terminal extensions 17, 17, adapted to fit into corresponding openings 18 in the plates 15, being burred over the plates after assembling to prevent displacement of the latter. The spacing of the plates 15 is maintained centrally by a spacer-pin 19, which is provided terminally with reduced extensions 20, 20, extending through suitable openings 21 provided in the plates 15, 15, and secured thereto in the same manner as the hinge-pin 16.

15 Supported between the outer ends of the plates 15, 15, forming a jaw, is a contact-roll 22 mounted to rotate freely upon an axle-pin 23 which is rigidly held in position by means of faceted terminal extensions 24, 24, which fit into corresponding slots 25 provided in the plates. In its preferred form, as shown, these extensions constitute polyhedral members, which in the process of manufacture are preferably formed by cutting away the body of the pin to accurate dimensions so as to insure the rigidity of the pin in its setting. Any looseness of the pin in this respect invites play which in time causes the contact-roll to wobble and bear unevenly on the ring 2. The modification shown in Figs. 12 and 13 illustrates an axle-pin 26 having terminal extensions 27, 27, provided with single flat faces formed by cutting away the margin on one side only. The axle-pin herein shown forms a simple unitary structure which, when subjected to a process of hardening after forming to provide a durable bearing surface, offers a substitute for the provision of a 40 separate hardened bushing, intervening the pin and the roller, as shown in my said pending application. Hardening of the axle-pin results in greatly extending the comparatively brief period in ordinary experience during which the contact-roll maintains an even engagement with the contacts 4, 4, etc., a condition essential to effective and reliable ignition.

50 The free end of the contact-arm is impelled outward and normally maintained in movable engagement with the insulation ring 2 and contacts 4, 4, etc., under the impulse of a torsion spring 28 carried on the hinge-pin 16 between the carrier-arms 14, 14, one end of the spring being extended outward to bear preferably against the underside of the spacer-pin 19 and the oppo-

site end being extended inward for engagement with the carrier 7. The outward swing of the contact-arm is limited positively preferably by means of a shoulder 29 provided on the outer face of each carrier-arm 14 near the base and forming a stop for engagement by the corresponding plate 15 at a predetermined point in the arc of swing 65 of the contact-arm (Fig. 8), the inner margin of the plates at their rear ends being preferably extended inward to provide suitable engagement members 30, 30.

Although not specifically stated in each 70 instance, it will be understood that the parts of my device included in the electric circuits are constructed of conductive material.

I claim:

1. An ignition timer having a rotor 75 mounted to rotate upon an axis and having a jaw with openings in its sides, a roller mounted in and arranged to travel with said jaw, and a roller journal having a hardened bearing portion for supporting the 80 roller and having reduced terminal extensions extending into said openings in the jaw, at least one of said terminal extensions and its corresponding opening in the jaw having coöperating peripheral locking means 85 for retaining the roller journal rigid with said jaw.

2. An ignition timer having a rotor mounted to rotate upon an axis and having a jaw, a roller mounted in and arranged to 90 travel with said jaw, and a roller journal having terminal extension members extending into opposite sides of said jaw and having a hardened bearing portion providing support for the roller, at least one of said 95 extension members having one or more facets adapted to coöperate with means on the corresponding side of said jaw to retain said journal in a stationary position relatively to the jaw.

3. A rotor for ignition timers having apertured jaw members 15, a roller 22 mounted on and arranged to travel with said jaw members, and a roller journal 23 having a hardened bearing portion and comprising faceted terminal extension members 24 extending into said jaw members, the jaw members being formed to coöperate with the terminal extension members to retain said roller journal in stationary position.

In testimony whereof, I have signed my name to this specification.

EDWARD B. JACOBSON.
